UNITED STATES PATENT OFFICE.

CARL GRÜNZWEIG, OF LUDWIGSHAFEN-ON-THE-RHINE, GERMANY.

PAPER-FASTENER.

SPECIFICATION forming part of Letters Patent No. 451,710, dated May 5, 1891.

Application filed September 25, 1890. Serial No. 366,076. (No model.)

To all whom it may concern:

Be it known that I, CARL GRÜNZWEIG, a subject of the King of Bavaria, residing at Ludwigshafen-on-the-Rhine, in the Kingdom of Bavaria, German Empire, have invented new and useful Improvements in a Device for Fastening Together Newspapers, Invoices, and other Loose Documents or Papers, of which the following is a specification.

10 This invention relates to a device for fastening together newspapers, invoices, and other loose documents or papers, &c., so that they can with facility be separately removed without injury.

15 In the accompanying drawings, Figure 1 is a vertical longitudinal section of my improved paper-fastener, showing sheets held by the same. Fig. 2 is a side view of the fastener distended. Fig. 3 is a top view of the same.

20 Fig. 4 is a longitudinal sectional view of a modification of the fastener. Fig. 5 is a plan view of the same. Fig. 6 is a side view of another modification, and Fig. 7 is a plan view of the same.

25 The invention, which will be described with reference to the accompanying drawings, consists in a fastener in the form of a solid or hollow elastic shank *a*, Fig. 4, provided in its length with one or more hollow elastic but-

30 tons or projections *b* and at its lower end with a head *c*. The papers or other articles to be fastened together having been perforated, the shank *a* is passed through them, and the tension which is applied to the shank in draw-

35 ing it through the papers causes the elastic button *b* to become depressed or distended, so that it will pass through the perforation in the papers, &c., whereupon it will instantly expand as soon as the pull on the shank

40 ceases. The documents are then confined, as can be seen from Fig. 1, between the projec-

tion *b* and the head *c*. In order to remove the documents from the fastener, the head *c* is pulled, so that the elastic button *b* can be drawn through the perforation exactly as before.

In Fig. 2 the shank *a* is represented in its distended condition, the elastic button *b* having disappeared in consequence of the pull exerted upon the shank. The shank *a* in the drawings is shown hollow; but it may be solid, as above stated.

I do not confine myself to the form of the button *b*, which may be spherical, dished, or of other form; but it is essential that it should be hollow. These forms may have recesses, perforations, or excisions, Figs. 4 and 5.

A ring *c'*, held by an enlargement *b'* on the end of the shank *a*, as in Fig. 4, may replace the head *c*.

The shank *a* may, instead of being made of elastic material, be composed of a rigid metallic tube or a metallic rod, the elastic button *b* being fixed between the two parts.

Having now fully described and ascertained the nature of my said invention and in what manner the same is to be performed, I declare that what I claim is—

A fastener for papers, &c., consisting of a solid or hollow elastic shank provided with a head at one end and one or more compressible and expansible spring-buttons between the end and head, substantially as herein shown and described, and for the purpose set forth.

In testimony whereof I have signed my name to this specification in the presence of two subscribing witnesses.

CARL GRÜNZWEIG.
